UNITED STATES PATENT OFFICE.

DAVID GOODMAN AND CONRAD CHARLES GOODMAN, OF PHILADELPHIA, PENNSYLVANIA.

DANCING AND REVOLVING FIGURES AND OPERATING MECHANISM THEREFOR.

1,318,071.

Specification of Letters Patent.

Patented Oct. 7, 1919.

Application filed May 3, 1919. Serial No. 294,547.

To all whom it may concern:

Be it known that we, DAVID GOODMAN and CONRAD C. GOODMAN, citizens of the United States, residing at Philadelphia, in the county of Philadelphia and State of Pennsylvania, have invented certain new and useful Improvements in Dancing and Revolving Figures and Operating Mechanism Therefor, of which the following is a specification, reference being had to the accompanying drawings.

This invention relates to an improved amusement apparatus, particularly of a type in which a plurality of revolving and dancing figures are employed, and an improved mechanism for operating the revolving and dancing figures.

The invention aims to provide an apparatus particularly adapted for the amusement of children, and one which is simple, efficient and practical in construction.

The invention further aims to provide a plurality of figures arranged in series, and means for revolving the series of figures, one following the other in a continuous circuit, and means for revolving each series, in fact the series will be rotating individually, but also at the same time, while they are traveling in a continuous circuit, thereby creating amusement.

A further object of the invention is to provide an apparatus of this general character including means whereby as the figures are revolving in a circuit, and independently of each other, and also at the same time, provision of means is afforded to impart vibrations to the figures, giving the effect that the figures are turning and vibrating, in order to portray the art of dancing.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be hereinafter set forth, shown in the drawings and claimed.

In the drawings:

Figure 1 is a view partly in section, and partly in elevation, of the improved appa-

ratus constructed in accordance with the invention.

Fig. 2 is a plan view.

Fig. 3 is a detail view of another form of gearing between the revoluble member or disk and the shaft of the revolving figures or dolls.

Fig. 4 is a view of a housing frame, showing mounted therein in elevation, a mechanism for imparting movement to the revolving disk, and the means for operating the series of dancing figures, as the table is in motion, the means for operating the figures simultaneously having a modified construction for accomplishing practically the same result as accomplished in Figs. 1 and 2.

Fig. 5 is a sectional view on line 5-5 of Fig. 4.

Fig. 6 is a sectional view through a housing, showing another means for imparting movements to the series of figures.

Fig. 7 is a detail view of a means for imparting the slight vibrations to the figures, so that such vibrations, together with the revolutions of the figures impart to those observing that the figures are portraying dancers.

Fig. 8 is a detail view of a portion of the means for imparting revoluble movements to the series of figures.

Fig. 9 is a detail sectional view through the center of a portion of the disk 27 showing the gear 9^a, and also showing the mounting of the pulley 30 on the stationary shaft or post 29, which acts as a support for the central portion of the top of the casing or housing of the apparatus.

Fig. 10 is a detail view showing how the arms 17 are mounted on the revoluble member or disk 7, showing the springs 18.

Referring to the drawings, 1 designates a suitable housing or casing, in bearings 2 of which a crank shaft 3 is mounted. The crank shaft has a handle 4 at one end, and a gear 5 at its other end. Mounted in any suitable manner upon a vertical support 6 (which is centrally of the housing or casing) is a supporting and operating disk 7. The under part of this disk has a depending flange 8 provided with gear teeth 9, 105 which are engaged by the teeth of a gear 5, so that when motion is imparted to the crank shaft, the supporting and revoluble disk 7 may rotate, in either direction, it depending upon the direction of rotation of 110

the crank. While the flange 8 is shown as provided with gear teeth 9, it is obvious that the teeth may be dispensed with if desired, and instead, the lower edge of the flange 8 5 may frictionally contact with the friction gear in place of the gear 5. By such an arrangement it will be seen that motion may be imparted to the disk 7, possibly not as positive as when using gears, but the friction 10 may be sufficient in order to rotate the disk 7. Also mounted upon the support and stationary therewith is a disk member 11, provided with an annular groove 12. The housing or casing in its upper wall is provided 15 with a circular slot 13, the central portion of the upper wall of the housing or casing is also mounted stationary relatively to the disk 11. A plurality of vertical shafts 14 are provided, which are supplied with 20 suitable friction gears 15.

The lower ends of the shafts 14, in Fig. 7, engage suitable brass sockets 16, which are countersunk into the rotating and supporting disk 7, thereby swivelly mounting 25 the shafts 14.

The shafts are also provided with arms 17, to which springs 18 are connected. These springs are carried by the rotating and supporting disk 7, and constitute means 30 to urge the vertical shafts, so as to keep their friction gears in constant frictional contact or engagement with the groove 12 of the disk 11, so that when the disk 7 is given revoluble movements, the shafts 14 35 will revolve. A plurality of figure supporting plates or members 20 have depending lugs 21. These lugs fit in the sockets of the upper ends of the shafts 14, so that when said shafts are rotated, the supporting plates 40 will likewise move or rotate so that the figures thereon will operate in a fashion, which will give the impression that the figures are dancing. The under faces of the plates are provided with projections 22, which will 45 contact and ride over similar projections 23 of the top of the housing or casing, thereby imparting vibrations to the plates, which together with the travel of the figures in a circuit, will create the impression that the 50 figures are dancing.

In Fig. 3 instead of the disk 11 being grooved, it is provided with teeth 24. These teeth are designed to mesh with the teeth of the gears 24^a, which are to be used in 55 lieu of the friction gears 15. The teeth 24 are mutilated, in other words a vacant space 25^a is provided, and when this space comes in contact with the teeth of the gear 24^a, the shaft 14^a will pause in its rotation, 60 thereby giving the impression that the figures are hesitating, while in the act of dancing.

The gear 5 is provided with a vacant space 10^a. This space, when it comes in contact 65 with the teeth 9 of the flange 8, the

rotating or supporting disk will pause, thereby giving the impression that the figures are hesitating.

In Figs. 4 and 5 a modified construction of means is provided for imparting motions to the series of figures individually, and at the same time, and this modified construction of means comprises a plurality of pulleys 25, one upon each of the vertical shafts 26. These shafts 26 are carried by the supporting and rotating disk 27. The plates 28 for the support of the figures are mounted on the upper ends of the shafts 26. A central post 29 has its lower end fixed to the bottom (not shown) of the housing or casing, and rises up from the bottom, and passes through the supporting and rotating disk 27, and its upper end engages a socket member 29^a Fig. 9, which is secured to the under face of the central portion of the top of the housing or casing. Revoluble upon the central post 29 is a pulley 30, and depending downwardly from the pulley is a key or projection 30^a, which engages a notch 30^b of the central opening in the disk 27, thereby making the disk fast with the pulley 30. It is obvious that when the disk is rotated, the pulley will in turn be rotated, which will transmit motion to the plurality of belts 31. These belts 31 engage the pulleys 25 and the pulley 30. The lower extremity of the key or projection 30^a also engages in a notch of the central opening in the gear 9^a, in order to insure rotation of the gear 9^a with the disk 27. The gear 9^a 100 is also fastened by the rivets or the like 27 to the disk 27. Each belt 31 is crossed at two points as indicated at 32, and the central portions of the belts are separated and engage the pulley 30 at diametrically opposite points. It is obvious that when the disk 27 is rotated, motions will be imparted to the belts through the medium of the pulley 30, which revolves with the disk 27, and which motions of the belts 31 are transmitted to the pulleys 25, thereby imparting the motions to the shafts 26. The lower ends of the shafts 26 are mounted in bearings of the disk 27. The arrows *a*, *b* and *c* indicate the direction of rotation of the disk 115 27, the pulleys 25 and 30, while the arrows *d* indicate the direction of travel of said belts.

In Fig. 6, a modified arrangement of belting is provided. In this construction, the central post of the supporting disk is provided with a pulley 33 provided with a plurality of grooves, which are engaged by a plurality of radial belts 34.

In applying the belts 31 (which are endless) the opposite sides of the belts are first 125 placed in engagement with diametrically opposite portions of the pulley 30, as indicated in Fig. 8, after which end portions of the belts are crossed, as at 32, as indicated in Fig. 5.

In Fig. 7, a modified construction of means for imparting vibrations to the figures is disclosed.

In Fig. 7 there is disclosed a large detail view in section of the mounting of one of the shafts 14, clearly showing one of the brass sockets 16, which is countersunk in the disk 7. Also in this figure there is shown a modified construction of a figure supporting plate 20. For instance, the plate 20 in Fig. 7 is provided with figure supporting members proper 20^a, each of which is provided with a depending pin 20^b, which passes through an opening in the plate 20, which is loosely mounted upon the upper end of the shaft 14, in such wise as to permit a slight vertical vibration of the plate 20, when the nubs 22 contact with the nubs 23. The looseness of play of each of the plates 20 with relation to the upper end of the shaft 14 is not sufficient to permit the plate 20 to sag at its outer end to the extent of dragging or contacting with the upper face of the top of the housing or casing. Secured in any suitable manner (not shown) to the lower ends of the pins 20^b are additional plates 20^c, which, in the structure of Fig. 7, carry the nubs 22, to engage the nubs 23. It is obvious that the structure in Fig. 7 relative to the plates 20 may be used in connection with the structures of Figs. 1, 2, 4, 5 and 6. Interposed between the figure supporting plates 20^a and the upper face of the plate 20 and in surrounding relation to the pins 20^b are washers 20^d. Additional washers 20^d are interposed between the plates 20^c and the under face of the plate 20 and in surrounding relation to the pins 20^b. By virtue of these washers, it is obvious that the figure supporting plates proper 20^a are held properly spaced, yet there is sufficient looseness of play between the plates 20, 20^a, and 20^c, whereby when the nubs 22 contact with the nubs 23 during the revoluble movements of the plates 20, the figure supporting plates 20^a may vibrate relatively to the plate 20. By means of this vibrating movement, it may be noted that the figures on the plate 20^a will in turn vibrate, thereby giving the impression that the figures are portraying certain steps or movements in dancing, say for instance, such movements as may result when fox-trotting. Also in Fig. 7 a modified form of spring means 14^a is illustrated for urging the shafts 14 in slightly inclined directions toward the periphery of the friction grooved disk 11, so as to insure friction between the friction gears 15 and the friction disk member 11.

The invention having been set forth, what is claimed as new and useful is:

1. In an amusement apparatus, the combination with a housing, the upper wall of which is provided with a circular slot or opening, of a rotatable supporting table

mounted in the housing, of a plurality of vertical shafts supported on the table at diametrically opposite points and provided with gears, of a stationary gear mounted in the housing and engaged by said gears of the shafts, whereby revoluble movements are imparted to said shafts, plates carried on the shafts and having figures representing dancers, and means for coöperating with the shafts for urging their gears in frictional contact with the stationary gear.

2. In an amusement apparatus, the combination with a housing having its upper wall provided with a circular opening, of a rotatable supporting member mounted in the housing, revoluble elements loosely supported upon said member at diametrically opposite points, means carried upon the revoluble member for imparting revoluble movement to the loosely mounted elements, said elements having supports provided with movable figures, loosely supported means carried by the members to support the figures and means carried by the top wall of the housing to be engaged by parts of the figure supporting means, whereby the figures may vibrate, as they move in a circular direction, and means for operating the revoluble member.

3. In an amusement apparatus, the combination with a housing having its upper wall provided with a circular opening, of a revoluble member mounted in said housing, means loosely mounted upon the revoluble member and movable in said circular opening, devices loosely mounted upon the upper portions of the loosely mounted means of the revoluble member and carrying figures, said devices having elements, means on the upper surface of the top to be engaged by said elements to vibrate the devices, as the loosely mounted means rotate, and means for operating the revoluble member.

4. In an amusement apparatus, the combination with a housing having its upper wall provided with a circular opening, a revoluble member mounted in the housing and provided with revoluble devices adapted to revolve in a circuit relatively different to the circuit of the revoluble member, said devices protruding through the circular opening, figure supporting elements carried by the devices loosely, intermittently coöperative means carried by the elements and the upper surface of the top wall, for vibrating the elements as the devices rotate.

5. In an amusement apparatus, the combination with a housing having its upper wall provided with a circular opening, a revoluble member mounted in the housing and provided with revoluble devices adapted to revolve in a circuit relatively different to the circuit of the revoluble member, said devices protruding through the circular open-

ing, figure supporting elements carried by the devices loosely, intermittently coöperative means carried by the elements and the upper surface of the top wall, for vibrating the elements as the devices rotate, means for rotating said devices and means for rotating the member.

6. In an amusement apparatus, the combination with a housing having its upper wall provided with a circular opening, of a plurality of revoluble elements protruding through the opening and provided with loosely and detachably connected figure supporting pieces, figures upon said pieces, said pieces adapted to rotate in a horizontal

plane, said pieces and the upper wall of the housing having intermittently coöperative connections, to cause said pieces to vibrate, and operative means revoluble in a plane parallel with the revoluble movement of the elements and carrying said elements and provided with means for rotating the elements and swinging the pieces in horizontal planes parallel with the horizontal plane of rotation of the operative means.

In testimony whereof we hereunto affix our signatures.

DAVID GOODMAN.

CONRAD CHARLES GOODMAN.
